(57) **CLAIM**

The ornamental design for a spray nozzle for a pressure washing machine, as shown and described.

DESCRIPTION

2.1: Perspective

2.2: Front; back view is a mirror image.

2.3: Top

2.4: Bottom

2.5: Right

2.6: Left

2.7: Partial enlarged view taken along line A-A in 2.2

2.8: Partial enlarged view taken along line B-B in 2.3

2.9: Partial enlarged view taken along lines C-C and D-D in 2.6

The product is a cleaning nozzle that is attached to a washing machine for machined parts. The broken lines in the reproductions depict portions of the spray nozzle for a pressure washing machine that form no part of the claimed design.
